UNITED STATES PATENT OFFICE.

DAVID F. DOMIZI, OF CLEVELAND, OHIO.

GEAR-LAPPING MACHINE.

Application filed September 17, 1924. Serial No. 738,134.

This invention relates to gear lapping machines, and more particularly to a machine in which a pair of mating gears may be adjusted accurately into proper meshing engagement with each other and in which the gears may be caused to act one upon the other by applying a coating of abrasive material to the teeth of one or both gears whereby when the gears are driven surface portions of the teeth are worn away in such manner that a substantially perfect meshing engagement may be obtained between the mating gears.

The machine herein disclosed is designed particularly for lapping the bevel ring and driving gears of the differential gearing employed in automobile transmissions.

An object of the present invention is to provide means whereby the gears to be lapped may be quickly and accurately adjusted into proper mesh with each other prior to the lapping operation.

A further object is to provide simple and efficient means for detachably and rigidly connecting the gears to the driving and driven spindles.

A further object is to provide convenient means for applying a load to the driven spindle and for varying such load at will as desired.

A further object is to provide means for protecting the operator from flying particles of abrasive material, the protecting means being so designed as not to interfere with the inspection of the gears during operation or with the application of the abrasive material thereto, the protective means also serving to prevent the abrasive material from getting into the bearings of the machine.

With the above and other objects in view, the invention may be said to comprise the machine as illustrated in the accompanying drawing hereinafter described and particularly set forth in the appended claims, together with such variations and modifications thereof as will be apparent to those skilled in the art to which the invention appertains.

Reference should be had to the accompanying drawings forming a part of this specification in which Fig. 1 is a side elevation of a machine embodying the invention, a portion of the movable spindle housing and of its adjusting and supporting means being broken away and shown in sec-

tion; Fig. 2 is a front elevation of the machine with a portion of the fixed spindle housing broken away and shown in section; Fig. 3 is a top plan view of the machine; Figs. 4 and 5 are a side and a front elevation respectively of the driving head and operating motor; Fig. 6 is a central vertical section taken through the driving head longitudinally thereof.

Referring to the accompanying drawings, in which the same parts are designated by the same reference numerals throughout, the machine is mounted upon a supporting stand 1 upon the top of which is mounted a spindle housing 2 which has a limited vertical and angular adjustment and a laterally adjustable spindle housing 3, the spindle housing 2 being disposed longitudinally of the stand and the adjustable housing 3 being disposed transversely thereof.

The housing 2 is rigidly clamped to the stand 1 by means of bolts 2^a and is mounted for slight angular adjustment about a pivot pin 2^b carried by the stand. The openings in the base of the housing through which the bolts 2^a extend are large enough to permit the slight angular adjustment. A limited vertical adjustment of the housing may be obtained by the use of shims 2^c of the desired thickness.

The adjustable housing 3 is mounted upon a carriage 4 which is adjustable longitudinally of the supporting stand 1. In order that the gears when adjusted into proper meshing engagement may be rigidly held in the positions to which they are adjusted means are provided for rigidly clamping the adjustable housing 3 in any position to which it may be desired.

The carriage 4 is provided with means whereby it may be rigidly clamped in any adjusted position to the fixed supporting stand 1. To this end the carriage 4 carries a bolt 5 which is rigidly secured to the carriage 4 and extends downwardly through a longitudinal slot 6 in the top of the supporting stand. The bolt 5 has a nut 7 at its lower end to which is connected an adjusting lever 8 which projects through a wall of the supporting stand. Surrounding the bolt 5 and resting upon the nut 7 is a sleeve 9 which carries at its upper end a clamping plate 10 which is moved when the nut 7 is turned in a tightening direction into clamping engagement with the top wall of the supporting stand. When the clamping plate 10 is

released the carriage 4 may be adjusted longitudinally but when the clamping plate 10 is held in clamping engagement with the top wall of the supporting stand, the carriage 4 is rigidly held against longitudinal movement. At its forward end the carriage 4 is provided with an integral bracket 11 which extends downwardly in front of the upper portion of the stand 1 and forms a support for a lead screw 12 by means of which the carriage 4 may be adjusted longitudinally of the frame. The lead screw 12 is journaled in a bushing 13 secured in the bracket 11 and is provided with an inner thrust flange or collar 14 bearing against the inner end of the bushing 13, the outer end 15 of the lead screw being reduced and having rigidly secured thereto a hand wheel 16, the hub of which bears against the outer end of the bushing 13. The hand wheel 16 is provided with a handle 17 by means of which may be turned and has a graduated rim 18 which cooperates with a stationary pointer 19 which is clamped to the bushing 13 and serves to indicate the amount of angular movement imparted to the hand wheel 16. The lead screw 12 passes through and has threaded engagement with a nut 20 fixed in the end wall of the supporting stand 1. The carriage 4 may be adjusted longitudinally of the frame by means of the lead screw 12, the extent of such movement being accurately ascertainable by means of the graduations upon the hand wheel and after being so adjusted the carriage 4 may be rigidly secured in adjusted position by means of the clamping bolt 5.

The housing 3 is transversely adjustable upon the carriage 4, the carriage 4 being provided with suitable transverse grooves to receive transversely extending ribs on the bottom of the housing 3. For adjusting the housing 3 the carriage 4 has an outwardly and upwardly extending bracket at the outer end thereof, and journaled in this bracket is a lead screw 22 which is rotatably mounted within a bushing 23 secured in the bracket 21. The lead screw 22 is held against longitudinal movement with respect to the bushing 23 by means of a thrust flange or collar 24 which bears against the inner end of the bushing 23, the outer end 25 of the lead screw 22 being reduced and having secured thereon a hand wheel 26, the hub of which bears against the outer end of the bushing 23. The hand wheel 26 is provided with a suitable handle 27 by means of which it may be turned to rotate the lead screw to adjust the housing 3. In order that the extent of adjustment of the housing 3 may be accurately determined, the hand wheel 26 has a graduated rim 28 which cooperates with a fixed pointer 29 clamped to the bushing 23. The lead screw 22 extends through and has a threaded engagement with a nut 30 fixed to

the housing 3. In order to rigidly clamp the housing 3 in its various adjusted positions upon the carriage 4, a bolt 31 is carried by the housing 3, extends through the bottom thereof and has its head 32 slideable in an undercuit groove 33 in the carriage 4. At its upper end the bolt 31 is provided with a nut 34, accessible through an opening 35 in the side wall of the housing 3, by means of which the bolt 31 may be tightened to rigidly clamp the housing 3 in any adjusted position on the carriage 4.

A tubular spindle 36 extends through the housing 2 longitudinally of the supporting stand and is journaled in a thrust bearing 37 in a rearward extension 38 of the housing and in an inwardly extending boss 39 carried by the front end wall of the housing. At the front end of the housing there is a ring gear supporting head 40 which has an integral tubular shank 41 which tapers rearwardly and fits within the tapered interior of the tubular spindle 36. Attached to the outer face of the head 40 is a centering disk 42 of a diameter to fit within a ring gear 43 secured to the head 40. A clamping plate or disk 43 cooperates with the head 40 to clamp a ring gear to the head, the clamping disk 43 being provided with finger holes 44 to facilitate rotation by hand. The clamping plate 43 has an interiorly threaded hub sleeve 45 which receives one threaded end of a clamping spindle 46 which extends through the inner tubular spindle 41 and carries nuts 47 at its rear end which engage with the flanged collar 47 fitting within the rear end of the tubular spindle 36 and bearing against the rear end thereof, the nuts 47 serving to rigidly clamp the disk 43 against the outer face of the ring gear 48 to rigidly secure the ring gear in place on the head 40 and to clamp the head 40 to the spindle.

The spindle 36, head 40, clamping disk 43 and ring gear 48 rotate as a unit and the spindle 36 within the housing 2 carries a large spiral gear 49 which serves to drive a transversely disposed countershaft 50 journaled in the housing above the spindle, the countershaft 50 being provided with a small spiral gear 51 meshing with the large spiral gear 49. At its forward end in front of the housing 2 the countershaft 50 has fixed thereto a brake drum 52 and cooperating with the brake drum 52 is a brake band 53 which has its ends projecting beneath the drum, one of the ends 54 projecting downwardly and secured between anchor lugs 55 projecting from the front face of the housing 2. The free end 56 of the brake band lies alongside the fixed end 54 and the ends 54 and 56 are engaged by a tightening bolt 57 which extends through the two ends and is provided at its outer end with adjusting nuts 58 by means of which the relative movement between the two ends of the brake

band may be adjusted. Adjacent its inner end and engaging the outer face of the movable end 56 of the brake drum is a collar 59 slidably mounted on the bolt 57, the collar 59 being provided on its outer face with a cam surface which cooperates with a similar cam surface on the head 60 of the bolt and held against rotation by means of a pin 59^a carried by the end 56 of the brake band. 5 The head 60 of the bolt is provided with a laterally projecting handle 61 by means of which the bolt may be turned. By turning the handle 61 in a downward direction the cam head 60 acts against the collar 59 forcing the same inwardly against the free end 56 of the brake band drawing the band into engagement with the brake drum 52. In the operation of the machine the spindle 36 is driven through the ring gear 48 and imparts a rotation at a higher rate of speed to the countershaft 50. By operating the lever 61 the operator can apply the desired braking force to the brake band and, since the speed of the brake drum 52 is greater than that of the spindle 36, a relatively light pressure upon the handle 61 is sufficient to apply a relatively heavy load to the spindle 36.

Journalized in the movable housing 3 is a tubular spindle 62 which is disposed with its axis in a plane with the axis of the spindle 36 and at right angles to said spindle. The tubular spindle 62 is journaled at its rear end in a thrust bearing 63 mounted in a rearward extension 64 to the housing 3 and at its forward end in a boss 64 extending inwardly from the front wall of the housing 3. Within the housing 3 the spindle 62 has fixed thereto a belt pulley 66 which is adapted to receive a belt running over an overhead line shaft, the housing 3 being provided with openings 67 through which the belt passes. The opening through the tubular spindle 62 is tapered rearwardly adjacent its forward end and is adapted to receive a tapered sleeve 68 within which fits the tapered stub shaft 69 of the small beveled driving gear 70. The stub shaft 69 has a reduced threaded rear end 61 which is screwed into a coupling sleeve 72 which is keyed to the interior of the spindle 62. A clamping spindle 73 is screwed into the rear end of the coupling sleeve 72, extends through a bushing 74 secured in the rear end of the tubular spindle 62 and is provided with clamping nuts 75 at the rear of the bushing 74 by means of which the clamping spindle 73, coupling sleeve 72 and stub shaft 69 may be drawn rearwardly to tightly clamp the tapered sleeve 68 in the spindle 62 and the tapered stub shaft 69 within the tapered sleeve 68. The small beveled pinion is thus rigidly clamped to the spindle 62 and rotates therewith. To protect workmen passing along the rear of the machine a guard plate 76 is secured over the rear end

of the clamping spindle 73 by means of a U-shaped bracket 77 rigidly secured to the rearward extension 64 of the housing 3. Secured to the housing 2 behind the head 40 and ring gear 48 is a guard plate 78 which is provided with a flange 79 along its upper and outer edges which project over the periphery of the ring gear so that any fine particles of abrasive material which may be thrown from the ring gear strike against the flanges 79 and cannot be thrown into the face of the operator. Behind the small gear 70 and secured to the movable housing 3, there is a guard plate 80 which has flanges 81 along its upper and outer side edges which overlie the periphery of the gear 70 and serve to deflect any particles of abrasive material thrown from the gear 70. To prevent the passage of abrasive material into the bearings of the small gear a guard disk 82 is secured to a sleeve 68 immediately behind the gear 70 and overlies the central opening in the guard plate 80 through which the spindle projects. Mounted on the stand 1 beneath the guard plates 78 and 80 is a drip pan 83 which catches the material thrown from the gears and deflected by the guard plates. The drip pan 83 also serves as a container for the abrasive material and liquid with which it is mixed for application to the gears. 95

In the operation of the machine the ring gear 48 and small driving gear 70 of a differential gearing are clamped to their respective spindles in the manner above described. The housing 3 is then adjusted by means of the lead screws 12 and 22 until the gear 70 meshes with the ring gear 48 with the desired amount to back lash. This adjustment may be made very accurately by utilizing the graduations of the hand wheels 16 and 26 in making the adjustments of the housing 3. Before starting the driving mechanism the gear may be coated with a liquid containing abrasive material such as emery powder and upon rotation of the driving spindle 62 the brake band 53 may be applied to impose the desired load upon the driven spindle 36. As the gears 48 and 70 are driven in mesh with each other, the teeth thereof are abraded by the abrasive material with which they are coated and the gears thus grind themselves into proper meshing engagement. The abrasive material may be applied to the gears during the operation of the machine by holding a paint brush which has been dipped in the mixture of liquid and abrasive material adjacent the inner edges of the teeth. The liquid and abrasive material thus applied is caused to flow by centrifugal force outwardly into the spaces between the teeth of the gears. This operation will be continued until the gears operate noiselessly and without any apparent interference. The machine shown herein may be used in connection with the 130

testing machine shown in my co-pending application Serial No. 729,667, filed Aug. 2, 1924, in which sound intensifying means is employed to detect imperfections not otherwise discernible.

It is in some instances desirable to mount the driving motor directly upon the machine and it is also advantageous to provide for a slight vertical adjustment of one of the 10 spindles with respect to the other. Figs. 4, 5 and 6 show a head for the driving spindle with a driving motor mounted thereon and provided with means for adjusting the driving spindle vertically.

15 The driving motor 84 carries a pulley 85 on the shaft thereof over which runs the driving belt 86, the motor 84 being supported upon a platform 87 carried at the upper ends of posts 88 which are slidably mounted at their ends in the spindle housing 3^a and yieldably supported by springs 89 which are interposed between the top of the housing and collars 90 adjustably secured to the posts. The springs 89 serve to hold the belt 20 86 taut and will yield to permit the belt to slip if an excessive load is imposed on the motor.

25 The tubular driving spindle 62 which is driven by the belt 86 through the pulley 66 and carries the small gear 70 which meshes with the large gear carried by the spindle on the fixed head may as shown in Figs. 5 and 6 be journaled eccentrically within an adjustable bushing 91 which is rotatably 30 mounted in the housing 3^a and is adapted to be turned to different positions of adjustment by means of a worm 92 meshing with a worm gear 93 formed on the periphery of the bushing, the worm 92 being carried by a shaft 94 which has a hand wheel 95 outside the casing. The worm 92 may be rotated to turn the bushing 91 to adjust the spindle 62 to the desired height and the bushing 91 may be secured in adjusted position by means of a nut 96 which is threaded on the forward end of the bushing and is adapted to be screwed against the front face of the housing 3^a. The bushing 91 is provided with a circumferentially extending slot 97 to receive the belt 86, the slot 97 being of sufficient length to permit the necessary angular adjustment of the bushing 91. After the spindle has been adjusted to the proper height the head 3^a which is mounted exactly as the head 3 in Figs. 1 to 35 3 may be adjusted in a direction longitudinally of the spindle 62 or transversely with respect thereto to bring the small gear 70 into proper mesh with the large gear on the spindle 36.

Having described my invention, I claim:

1. In a machine of the character described, a supporting stand, a spindle mounted thereon, means for detachably securing a gear to said spindle, a second spin-

dle movably mounted on said stand, means for detachably securing a gear to said last mentioned spindle, means for adjusting the movable spindle longitudinally of the first mentioned spindle or transversely thereof 70 to bring the detachably secured gears on the spindles into mesh, driving means connected with one of the spindles, a brake connected with the other of the spindles, and manually operable means for applying the 75 brake by which the pressure between the teeth of the intermeshing gears on the spindles may be varied as desired during operation of the machine.

2. In a machine of the character described, a supporting stand, fixed and adjustable spindles mounted on the stand, means for driving one of the spindles, a countershaft geared to the other of the spindles, a brake on the countershaft, and manually operable means for applying the brake by which the pressure between the teeth of the intermeshing gears on the spindles may be varied as desired during operation of the 80 machine.

3. In a machine of the character described, a supporting stand, angularly disposed driving and driven spindles mounted on the stand, means for detachably securing bevel gears to said spindles, means for adjusting one of the spindles relatively to the other to bring the bevel gears into mesh, means for driving the driving spindle, a countershaft, gearing between the countershaft and driven spindle adapted to drive the countershaft at a rate of speed higher than that of the spindle, a brake on said countershaft, and manually operable means for applying the brake by which the pressure between the teeth of the intermeshing 95 gears on the spindles may be varied as desired during operation of the machine.

4. In a machine of the character described, a supporting stand, angularly disposed driving and driven spindles mounted on the stand, means for detachably but rigidly securing bevel gears to the spindles, means for adjusting one of the spindles longitudinally and transversely with respect to the other to bring the gears thereon into 100 mesh and to vary intermeshing engagement thereof, means for driving one of the spindles, and guard plates secured to the stand at the rear of each of the bevel gears, said plates having flanges extending outwardly 105 over the peripheries of the gears.

5. In a machine of the character described, a supporting stand, a spindle mounted on said stand, means for detachably but rigidly securing a bevel gear to said spindle, a carriage mounted for linear movement on the stand, a spindle mounted for linear movement on the carriage in a direction transverse to the direction of movement of the carriage, means for detachably but 110 rigidly securing a gear to said spindle, a second 115

idly securing a bevel gear to said spindle, means for adjusting said carriage and spindle to bring the gears into adjusted meshing engagement and for rigidly securing the carriage and spindle in adjusted position, means for driving one of the spindles, and means for impeding the rotation of the other of the spindles.

6. In a machine of the character described, a pair of spindles mounted at right angles to each other with the inner ends thereof adjacent, means for adjusting one of the spindles longitudinally of its axis and in a direction at right angles thereto, means for detachably fixing bevel gears to the inner ends of the spindles, guards mounted behind each of the gears, said guards having portions overhanging the peripheries of the gears, and means for driving one of the spindles.

7. In a machine of the character described, a supporting stand, a housing fixed thereto, a guard in the form of a plate secured to the inner face of the housing, a spindle mounted in the housing, said spindle projecting through the guard, a second housing adjustably mounted on the stand, the inner face of the second housing being at right angles to the inner face of the first, a guard in the form of a plate secured to the inner face of the adjustable housing, a spindle carried by the adjustable housing and having its inner end projecting through the guard plate, means for detachably fixing bevel gears to the spindles outside the guards, said guards having flanges overlying the peripheries of the bevel gears.

8. In a device of the character described, a supporting stand, a pair of relatively adjustable housings mounted on the stand, said housings having inner faces disposed at right angles with respect to each other, spindles mounted in said housings, said spindles projecting beyond the inner faces of the housing, means for clamping a bevel ring gear to the projecting end of one of the spindles, means for clamping a small driving bevel gear to the other of the spindles, guards secured to the housings behind the gears, said guards having outwardly extending flanges along their upper and outer side edges overlying the gears, and a drip pan beneath the gears and guards.

9. In a device of the character described, a supporting stand, a pair of relatively adjustable housings mounted on the stand, said housings having inner faces disposed at right angles with respect to each other, spindles mounted in said housings, said spindles projecting beyond the inner faces of the housings, means for clamping a bevel ring gear to the projecting inner end of one of the spindles, means for clamping a small driving bevel gear to the inner end of the other of the spindles, guard plates secured

to the housings behind the respective gears, said guard plates having flanges overlying the peripheries of the gears, a disk secured to the spindle carrying the small gear, said disk being secured immediately behind the gear and covering the opening in the guard plate through which the spindle projects.

10. In a machine of the character described, a supporting stand, a carriage mounted for linear movement on the stand, a lead screw for adjusting the carriage, a housing mounted for linear movement on the carriage in a direction at right angles to the direction of movement of the carriage, a lead screw for adjusting the housing, hand wheels fixed to the lead screws, said hand wheels having graduated rims, a fixed pointer cooperating with each of the graduated rims, means for clamping the carriage and housing in adjusted positions, a spindle carried by said housing, means for clamping a bevel gear thereto, a fixed spindle mounted on the stand at an angle to the first mentioned spindle, means for clamping a bevel gear to the fixed spindle in a position where the first mentioned gear may be adjusted into meshing engagement therewith, means for driving one spindle, and means for impeding the rotation of the other spindle.

11. In a machine of the character described, a supporting stand, a tubular spindle journaled therein, said spindle having an opening therethrough tapered toward its outer end, a clamping head, having a tubular tapered shank fitting in the tapered opening of the tubular spindle, a centering disk secured to the outer face of the head and adapted to fit within a ring gear, a clamping disk adapted to clamp a ring gear to said head, a clamping rod secured to the center of the disk and extending through the head and tubular spindle, and means engaging the rod at the rear end of the spindle drawing the clamping disk into clamping engagement with the ring gear.

12. In a machine of the character described, a supporting stand, a housing mounted thereon for angular adjustment about a vertical axis, means for rigidly securing said housing in adjusted position, a spindle journaled in said housing, means for detachably securing a gear to said spindle, a second housing movably mounted on the stand, a spindle journaled in the second housing and extending at an angle to the first spindle, means for detachably securing a gear to the second spindle, means for adjusting the second housing longitudinally or transversely with respect to said first spindle to bring the gears on the spindles into mesh, driving means connected with one of said spindles, and means for imposing varying loads on the other spindle.

13. In a machine of the character described, a supporting stand, a housing mounted thereon, said housing being adjustable vertically and angularly about a vertical axis, means for rigidly securing said housing in adjusted position, a spindle journaled in said housing, means for detachably securing a gear to said spindle, a second housing movably mounted on the stand, a second spindle journaled in the second housing and extending at an angle to the first mentioned spindle, means for detachably se-

curing a gear to the second spindle, means for adjusting the second housing longitudinally or transversely with respect to the first spindle to bring the gears into mesh, means for rigidly securing the second housing in adjusted position, means for driving one spindle, and means for imposing varying loads on the other spindle. 15 20

In testimony whereof, I hereunto affix my signature.

DAVID F. DOMIZI.
